UNITED STATES PATENT OFFICE.

PAUL PIGNOT, OF YONKERS, NEW YORK, ASSIGNOR TO ALEXANDER SMITH & SONS CARPET COMPANY, OF SAME PLACE.

DESIGN FOR A CARPET.

SPECIFICATION forming part of **Design No. 14,105, dated July 17, 1883.**

Application filed May 4, 1883. Term of patent 3½ years.

To all whom it may concern:

Be it known that I, PAUL PIGNOT, of Yonkers, Westchester county, New York, have invented a new and original Design for Carpets, 5 of which the following is a specification.

The accompanying photograph illustrates my new design for carpets.

This invention relates to a new design for carpets, oil-cloths, and analogous fabrics; and 10 it consists of the new ornamentation of parts hereinafter more fully pointed out.

On the ground of the carpet is a collection 15 of fanciful figures, *a*, of peculiar outline, clearly shown in the photograph, which in their collection produce a figure of their own. Another collection of figures, *b*, is of rhomboidal form, each ornament thereon or figure being

a curvilinear quadrangle with a square field in the middle and a dot in said field, all as shown. Another angular figure, *d*, of very 20 peculiar outline, is placed on the background of the carpet. The remaining parts of the carpet are covered by a bouquet, *A*, of flowers, the sprays whereof reach into the space between said groups of figures *a b d*, partly overlapping the latter, as shown.

I claim—

The design for carpets, consisting of the floral figure *A* and figures *a b d*, substantially as shown.

PAUL PIGNOT.
